EMIL LEINDORF AND NOAH PHILIP NORMAN, OF NEW YORK, N. Y.

SLIDING AND SWINGING WINDOW AND SASHES

Application filed October 21, 1929. Serial No. 401,020.

This invention relates to new and useful improvements in a slidable and pivotal window.

The invention has for an object the provision of a device of the class mentioned which is of simple durable construction, dependable in use and efficient in action, and which can be manufactured and sold at a reasonable cost.

10 The invention proposes a screened frame provided with inner and outer sashes, the inner sash consisting of a central portion hinged at one side to a slide strip and means for latching the other side of the central portion to a second slide strip, the outer sash consisting of a central portion of several hingedly connected sections with the outer end of the first section hingedly connected with a slide strip and the outer end of the 15 last section provided with latching means for connection with a second slide strip, and weather strips for providing a weather-proof structure.

For further comprehension of the invention, and of the objects and advantages thereof, reference will be had to the following description and accompanying drawings, and to the appended claims in which the various novel features of the invention are 20 more particularly set forth.

In the accompanying drawings forming a material part of this disclosure:—

Fig. 1 is an outer elevational view of a window constructed according to this invention.

Fig. 2 is an inner elevational view of the window shown in Fig. 1.

Fig. 3 is an enlarged horizontal sectional view taken on the line 3—3 of Fig. 2.

40 Fig. 4 is a fragmentary enlarged sectional view taken on the line 4—4 of Fig. 2.

Fig. 5 is an enlarged fragmentary sectional view taken on the line 5—5 of Fig. 2.

45 Fig. 6 is a fragmentary sectional view taken on the line 6—6 of Fig. 4.

Fig. 7 is a fragmentary sectional view taken on the line 7—7 of Fig. 3.

50 Fig. 8 is a fragmentary enlarged detailed view of a portion of Fig. 2.

Fig. 9 is a fragmentary sectional view taken on the line 9—9 of Fig. 8.

Fig. 10 is a fragmentary sectional view taken on the line 10—10 of Fig. 9.

Fig. 11 is an enlarged fragmentary detailed view of a portion of Fig. 3.

The slidable and pivotal window consists of a screened frame 12 provided with an inner sash 13, an outer sash 14, the inner sash consisting of a central portion 15 hinged at 60 one side 16 to a slide strip 17 and means for latching the other side of the central portion to a second slide strip 18, the outer sash 14 consisting of a central portion 19 of several hingedly connected sections 20, 21 and 22 with the outer end 23 of the section 20 hingedly connected with a slide strip 24 and the outer end of the section 22 provided with latching means for connection with a second slide strip 26, and weather strips for 65 providing a weather-proof structure.

The said screened frame 12 consists of side-forming members 27, a top-forming member 28 and a bottom-forming member 29. A screen 30 is attached across the outer 75 side of the frame 12. The inner and outer sashes 13 and 14 respectively are separated from each other by parting sash strips 31. An inner sash guide strip 32 is attached upon each of the side-forming members 27 for 80 slidably holding the inner sash, and an outer sash guide 33 is connected with each of the side-forming members 27 for slidably holding the outer sash. The side-forming members 27 are of hollow construction and arranged for housing conventional counterweights 34 connected with the sashes in customary fashion. Removal portions 35 are formed in the side-forming members 27 and in the inner sash guide strips 32 for permitting excess to the counterweights 34. Preferably these removable portions should be held in place by screws 36.

The said means for latching the free end of the inner sash 13 consists of a tapered dovetailed groove bracket 37 attached upon the top of the slide strip 18 and arranged with its wide portion at the bottom and is engageable by a flared catch 38 attached upon the top edge of the central portion 15 95

of the window sash, and the said flared catch being tapered for engaging in the tapered dovetailed groove of the bracket. Both the bracket and the catch are of substantially small height depending upon the latching 5 positions of a catch 39 for latching the slide strip 18 to the side-forming member 27.

The said catch 39 consists of an inverted U shaped strip 40 attached upon the top 10 of the slide strip 18 and slidably supporting a bolt 41 having a portion extending thru a slot 42 in the strip 40 and connected with a handle 43 for its operation. The bolt 41 may engage in lower aperture 44 or upper 15 aperture 45 of a bolt receiving plate 46 which is attached upon the side-forming member 27. The distance between the apertures 44 and 45 determine the referred to height of the bracket 37 and catch 38.

20 The said outer sash 14 has a special hinge 47 for connecting the sections 20 and 21. This hinge consists of a stationary portion 48 mounted upon the section 20 and an extremely long portion 49 extending across a 25 portion of the section 20 and connected with the section 20 by an interposed hinge joint 50. The said means for latching the free end of the section 22 to the slide strip 26 is identical with the means for latching the free 30 end of the central portion 15 to the slide strip 18. This may be evidenced by an inspection of the right and left portions of Fig. 3.

35 In Figs. 3 and 7, a catch 51 has been illustrated for latching the inner and outer sashes together while in closed position. This catch 51 consists of a plunger slidably mounted in the inner section and engageable in an aperture 52 in the outer section when in a depressed position. When pulled outwards the 40 plunger is disengaged from the aperture and motion of the sashes is possible.

45 The said outer sash guide strip 33 extends over the slide strips 24 and 26 indicated by reference numeral 53 and for the purpose of simulating a weather strip. A metal weather strip 54 projects at right angles to the outer sash guide strip 33 on one side of the frame only, namely on the right hand side. A rib 55 projects from the parting strip 31 at right 50 angles thereto and from the bottom to substantially the central portion only of one of the side-forming members 27, namely, the left hand one as viewed in Fig. 3. This rib also simulates a weather-proof strip.

55 Referring particularly to Fig. 3, dot and dash lines 56 indicate the outer sash in folded position and at an inclination immediately before resting against the side-forming member 27. This is one of the positions which 60 this sash may assume. If desired, the hinge section 48 may be moved to a position upon the section 20 so that the folded window may engage within the frame 12 and be substantially in the same plane thereof. This is 65 accomplished by a screw 57 rotatively

70 mounted in the section 20 and having its head 58 reachable from one end of the section 20 and threadedly engaging a lug 59 projecting from the hinge section 48. This lug may move in a recess 60 formed in the sash section 20. Rotation of the screw is possible to cause the section 48 to move to the left hand end of the recess 60 and then the window sash in folded position may assume the position stated.

75 While we have shown and described the preferred embodiment of our invention, it is to be understood that we do not limit ourselves to the precise construction herein disclosed and the right is reserved to all changes and modifications coming within the scope of the invention as defined in the appended claims.

80 Having thus described our invention, what we claim as new, and desire to secure by United States Letters Patent is:—

85 1. A slidable and pivotal window, comprising a screened frame provided with inner and outer sashes, the inner sash consisting of a central portion hinged at one side to a slide strip and means for latching the other side of the central portion to a second slide strip, the outer sash consisting of a central portion of several hingedly connected sections with the outer end of the first section 90 hingedly connected with a slide strip and the outer end of the last section provided with latching means for connection with a second slide strip, and weather strips for producing a weather-proof structure, said means for latching the other side of the central portion of the inner sash to the second slide strip consists of a tapered dovetailed groove bracket mounted upon the slide strip and engaged by a flared catch mounted upon the central portion and both of these elements being of a height substantially equal to the distance between apertures in a catch plate mounted upon the frame and engageable by the bolt of a catch arranged upon the slide strip.

95 2. A slidable and pivotal window, comprising a screened frame provided with inner and outer sashes, the inner sash consisting of a central portion hinged at one side to a slide strip and means for latching the other side of the central portion to a second slide strip, the outer sash consisting of a central portion of several hingedly connected sections with the outer end of the first section 100 hingedly connected with a slide strip and the outer end of the last section provided with latching means for connection with a second slide strip, and weather strips for producing a weather-proof structure, the hingedly connected sections of the outer sash being arranged to fold close to each other and then 105 assume an inclined position against one side of the said frame, and a means for shifting the hinge between certain of said sections so that the sash in folded position may assume a 110 120 125 130 135

position within the plane of the said frame.

3. A slideable and pivotal window, comprising a screened frame provided with inner and outer sashes, the inner sash consisting of a central portion hinged at one side to a slide strip and means for latching the other side of the central portion to a second slide strip, the outer sash consisting of a central portion of several hingedly connected sections with the outer end of the first section hingedly connected with a slide strip and the outer end of the last section provided with latching means for connection with a second slide strip, and weather strips for producing a weather-proof structure, the hingedly connected sections of the outer sash being arranged to fold close to each other and then assume an inclined position against one side of the said frame, and a means for shifting the hinge between certain of said sections so that the sash in folded position may assume a position within the plane of the said frame, said means consisting of a lug projecting from the section of the hinge and extending into a recess in one of the sash sections and threadedly engaged by a screw rotatively mounted in the sash section.

In testimony whereof we have affixed our signatures.

EMIL LEINDORF.
NOAH PHILIP NORMAN.
